UNITED STATES PATENT OFFICE.

DANIEL B. LUTEN, OF INDIANAPOLIS, INDIANA.

REINFORCING-BAR.

1,070,903.

Specification of Letters Patent. Patented Aug. 19, 1913.

Original application filed April 29, 1901, Serial No. 57,951. Divided and this application filed July 26, 1911. Serial No. 640,712.

To all whom it may concern:

Be it known that I, DANIEL B. LUTEN, a citizen of the United States, residing at Indianapolis, in the county of Marion and State of Indiana, have invented a new and useful Improvement in Reinforcing - Bars, of which the following is a specification.

My invention relates to improvements in reinforced concrete and has for its purpose 10 to provide a reinforcing bar with corrugations such that a maximum of tensile resistance may be developed in the embedded bar, with minimum materials and cost.

This application is a division of an application filed by me on April 29, 1901, Serial 15 No. 57,951.

My invention is illustrated in the accompanying drawing representing a longitudinal section through a bar of my improved 20 type.

The reinforcing bar 10 is provided with projections 11 spaced at intervals a from one another and with such elevation b above the surface of the bar, that with unit width of 25 bar, the shearing strength of the thickness a of the embedding concrete between projections will be greater than the crushing strength of the height b of such concrete immediately adjacent the forward face of the 30 projection. When such a bar is embedded in concrete, subsequently thoroughly hardened, and the bar subjected to tension tending to make it slip longitudinally through the concrete, failure will occur by the projections crushing the concrete bearing against them. If however the shearing strength through dimension a were less than the 35 crushing strength of dimension b , then the bar would have an excess of strength 40 against crushing and failure would occur by shearing off of the concrete between projections on lines parallel to the axis of the bar. Failure of the latter kind would be much 45 more serious than that of the former, because shearing of all the concrete between projections would occur simultaneously so as to result in a sudden release of the bar throughout its length. On the other hand if failure occurs by crushing at each face of 50 the projections, there will be only a slight yielding of the bar at the instant that the concrete gives way under the pressure of the face of the projection, and this crushing effect immediately powders the concrete di-

rectly in front of the projection so as to distribute the load radially against the surrounding uncrushed concrete, thus producing an immediate increase of bearing area at each projection on the solid concrete, and of increased density of material at the immediate surface of contact. Hence the bar, instead of pulling out clean, will but make a start toward failure when it is immediately arrested until greater tension is applied. It is therefore important that the projections 55 be spaced so far apart that failure will occur by crushing rather than by shearing. If the projection is of uniform height across the bar, this relation which is expressed by height of projection to distance between projections must be less than crushing strength to shearing strength. Now the crushing strength of concrete is approximately 2,000 lbs. per sq. inch, and the shearing strength about 200 lbs. per sq. inch. Hence the projections should be spaced apart approximately 70 more than 10 times their height. 75

Corrugated bars made hitherto have not conformed to this requirement, but have the projections close together. As a consequence 80 tests have shown them to fail suddenly by shearing a hole through the concrete sufficient to permit the passage of the bar and its projections. Moreover waste material results; because more metal is required to 85 space the corrugations close together wherefore waste and inefficiency go hand in hand. On the contrary in my arrangement of corrugations at distances more than ten times 90 their height metal is saved and efficiency 95 and safety increased.

I claim:

1. A reinforcing bar for concrete, provided with projections of such height and spacing that the space between adjacent 95 projections is more than ten times the height of the projections.

2. A reinforcing bar for concrete, provided with projections of such height and spacing that the space between two adjacent projections bears a greater ratio to the height of the projections than that of the crushing strength to the shearing strength 100 of concrete.

3. A reinforcement for hardened plastic 105 comprising a longitudinal member provided with projections of such height and spacing that the shearing area of embedding

hardened plastic between two adjacent projections bears a ratio to the bearing area of the rear projection greater than the ratio of crushing strength to shearing strength of the embedding hardened plastic.

In witness whereof, I have hereunto set my hand and seal at Indianapolis, Indiana,

this 20th day of July, A. D. one thousand nine hundred and eleven.

DANIEL B. LUTEN. [L. S.]
